UNITED STATES PATENT OFFICE

110,578

DESIGN FOR A WRIST WATCH CASE

Harold Bentler, Los Angeles, Calif.

Application March 16, 1938, Serial No. 75,879

Term of patent 14 years

To all whom it may concern:

Be it known that I, Harold Bentler, a citizen of the United States, residing at Los Angeles, in the county of Los Angeles and State of California, have invented a new, original, and ornamental Design for a Wrist Watch Case, of which the following is a specification, reference being had to the accompanying drawing, forming a part thereof.

Fig. 2 is a side elevational view thereof looking at the watch case from the right toward the left of Fig. 1.

Fig. 3 is a rear or bottom plan view of my wrist watch case.

I claim:

The ornamental design for a wrist watch case, as shown.

HAROLD BENTLER.
